M. M. FLOYD.
EXTENSION LADDER.
APPLICATION FILED FEB. 18, 1908.

910,188.

Patented Jan. 19, 1909.

UNITED STATES PATENT OFFICE.

MILTON M. FLOYD, OF GREENVILLE, ILLINOIS.

EXTENSION-LADDER.

No. 910,188.

Specification of Letters Patent.

Patented Jan. 19, 1908.

Application filed February 18, 1908. Serial No. 416,542.

To all whom it may concern:

Be it known that I, MILTON M. FLOYD, a citizen of the United States, residing at Greenville, in the county of Bond and State 5 of Illinois, have invented certain new and useful Improvements in Extension-Ladders, of which the following is a specification.

This invention relates to extension ladders, the object being to provide a ladder 10 which is so constructed that the extensible section will be automatically supported in its adjusted position.

Another object of my invention is to provide a supporting member which will support the extensible section rigidly, and at 15 the same time have the tendency to bring the two sections together, whereby the two sections will be held in their proper position, without any danger of them moving.

Another object of my invention is to provide novel means for limiting the outward movement of the supporting member, whereby it will be prevented from being thrown 20 outwardly by the extensible section when being drawn upwardly.

These objects are obtained by the novel arrangement and construction of parts hereinafter fully described and shown in the accompanying drawings, in which:—

Figure 1, is a perspective view of my improved ladder. Fig. 2, is a side elevation of the same, and, Fig. 3, is a section taken on line 3—3 of Fig. 2.

In the drawings A, indicates the base section, comprising the uprights 1—1 and a single set of rungs 2. The uprights 1—1 are provided with guide brackets B, adjacent to their upper ends. These extend outwardly from the edges of the side bars or uprights 40 flush with the inner side of the same, and between them and the uprights 1—1 is slidably mounted an extensible section C comprising the uprights 3—3 and rungs 4. The upper section is held in place between 45 the members 1—1, B—B by a U-shaped cross bar D, secured to the uprights 1—1 and is operated by a cable which is connected to its lower rung and passes over a pulley E, carried by the rung A', of the 50 base section A, and by means of which the extensible section is raised when desired, as will be hereinafter fully described.

Bearing plates F, are secured to the side bars of the section A, and extend outwardly, 55 and have their free ends connected to the brackets B, and in which are mounted the

outwardly extending journal arms G' and G² of a U shaped supporting frame G, which is adapted to extend between the rungs of the ladder sections and support the 60 extensible section. The bearing plates are slightly above the rung A', upon which the frame G, is adapted to rest, whereby the side bars of the frame will be slightly inclined, so that when it is engaged by one of the 65 rungs of the extensible section, and weight is brought on the same, it will have the tendency to draw the extensible section tightly down on the base section.

The plates F comprise a portion 5 secured 70 to the outer faces of the uprights 1—1, and off set portion 6 at right angles thereto which is securely fastened to the front face of the uprights and the bearing portion 7 extending outwardly in a plane parallel with the 75 portion 5.

The journal arms G' and G², form braces for the side bars of the extensible section C, whereby when the ladder is placed against a building, and a weight is placed on the same, 80 the side bars will be forced outwardly against the journal arms, which will prevent the section from giving and hold it rigidly in position.

The frame G, acts as a gravity pawl, as 85 the extensible section is moved upwardly, and to prevent the frame from being swung outwardly too far by coming into contact with the rungs of the extensible section, I provide the journal arm G², with an angle 90 end G³, which engages the portion 6 of the plate F on the side bar of the base section, and forms a stop for the frame.

In order to be able to operate the supporting frame from the ground, I form the journal arm G', with a lever G⁴, to which is connected a cable, whereby the frame can be held out of the path of the rungs of the extensible section, so that it can be readily lowered when desired.

From the foregoing description it will be seen that I have provided an extension ladder formed of two sections, one sliding upon the other in such a manner that it will be held in its proper position at all times and 105 under all conditions, thereby overcoming the difficulties now existing with ladders of this character now in use.

Having thus described my invention what I claim as new and desire to secure by Letters Patent is:—

An extension ladder comprising a base

100

2
section formed of a pair of uprights and a single set of rungs in combination with an extensible section formed of a pair of uprights and rungs, said extensible section being slightly narrower and arranged between the uprights of the base section which form guide ways for the same, brackets fixed to the front edges of said uprights and having their inner faces in a plane with the inner faces of said uprights, a U-shaped cross bar fixed to the uprights of the base portion and holding the extensible section in position, bearing plates fixed to said bracket and hav-

ing off set portions secured to the base section, a frame journaled in said plates and provided with a stop for engaging one of said off set portions for limiting the outward movement of said frame, substantially as described. 15

In testimony whereof I have signed my name to this specification in the presence of two subscribing witnesses.

MILTON M. FLOYD.
